DESIGN FOR A COMBINED PISTOL HOLSTER AND KNIFE SCABBARD

Merritt C. Pratt, United States Army,
Chicago, Ill.

Application April 27, 1945, Serial No. 119,272

Term of patent 14 years

(Cl. D22—6)

To all whom it may concern:

Be it known that I, Major Merritt C. Pratt, an officer of the United States Army, a citizen of the United States of America, residing in Chicago, Illinois, have invented a new, original, and ornamental Design for a Combined Pistol Holster and Knife Scabbard, of which the following is a specification, reference being had to the accompanying drawing, forming a part thereof.

The essential features of my design reside in the parts shown in full lines. The tie-string has been shown fragmentarily in Figs. 1 and 2 for convenience of illustration.

I claim:

The ornamental design for a combined pistol holster and knife scabbard, as shown and described.

MERRITT C. PRATT.
